CLAIM

I claim the ornamental design for a strap, as shown and described.

DESCRIPTION

(63) Continuation of application No. 29/309,002, filed on Jun. 10, 2008, now abandoned.

FIG. 1 is a perspective view of the strap of the present invention;

(30) Foreign Application Priority Data

FIG. 2 is a bottom plan view of the strap of FIG. 1;

Oct. 12, 2007 (BR) D16705289-4

FIG. 3 is a frontal view of the strap of FIG. 2;

(51) LOC (9) Cl. 03-01

FIG. 4 is a top plan view of the strap of FIG. 3; and

(52) U.S. Cl. D3/327

FIG. 5 is a side view of the strap shown in FIGS. 1 to 4 above.

(58) Field of Classification Search D3/318,

FIG. 6 is a perspective view of the second embodiment of the

D3/321, 324, 326, 327; 150/100, 107, 118

strap of the present invention;

See application file for complete search history.

FIG. 7 is a bottom plan view of the strap of FIG. 6;

(56) References Cited

FIG. 8 is a frontal view of the strap of FIG. 7;

U.S. PATENT DOCUMENTS

FIG. 9 is a top plan view of the strap of FIG. 8; and,
